UNITED STATES PATENT OFFICE.

CHARLES W. MILLER, OF CANTON, OHIO, ASSIGNOR TO THE GILLIAM MANUFACTURING COMPANY, OF SAME PLACE.

DESIGN FOR A SADDLETREE.

SPECIFICATION forming part of Design No. 30,276, dated February 28, 1899.

Application filed February 4, 1899. Serial No. 704,588. Term of patent 14 years.

To all whom it may concern:

Be it known that I, CHARLES W. MILLER, a citizen of the United States, residing at Canton, in the county of Stark and State of Ohio, have invented and produced a new and original Design for a Saddletree, of which the following is a specification, reference being had to the accompanying drawings, forming a part thereof.

Figure 1 is a perspective view of a saddle-tree, showing my new design. Fig. 2 is a transverse sectional view on line 2 2 of Fig. 1; and Figs. 3 and 4 are transverse sectional views on lines 3 3 and 4 4 of Fig. 1, respectively.

The saddletree embodying my design, as shown in the drawings, is of the usual form in the following respects, viz: It is a long narrow metal plate transversely curved midway between its ends to form two arms A A', which extend outward and downward at an angle to each other of ninety degrees, more or less. On each arm is formed what is known as a "box" B, which includes the longitudinally-extended ribs b and the top plate b', which extends between and is integral with the top edges of said ribs. These ribs extend longitudinally from points near the curved

middle part of the tree to points near the ends of the arms thereof, and they lie back from the margins of said arms a quarter of an inch, more or less.

The leading or material features of my design, as shown in the drawings, consist in the peculiar form of the edges of a saddletree of the character described—that is to say, of the parts of such a tree lying outside of the box and the ribs, which form parts thereof. These parts or edges appear to be curved upward from said box to their margins; or to otherwise describe the form of these edges, as shown, they are transversely convex on their under sides and transversely concave on their upper sides, being highest at their margins.

Having described my invention, what I claim as new, and desire to secure by Letters Patent, is—

The design for a saddletree as herein shown and described.

In testimony whereof I hereunto affix my signature in the presence of two witnesses.

CHARLES W. MILLER.
